UNITED STATES PATENT OFFICE.

HARRY W. ADAMS, OF MINNEAPOLIS, MINNESOTA.

TRACTION-MACHINE.

1,300,093.

Specification of Letters Patent. Patented Apr. 8, 1919.

Application filed April 26, 1915. Serial No. 23,873.

To all whom it may concern:

Be it known that I, HARRY W. ADAMS, citizen of the United States, resident of Minneapolis, county of Hennepin, State of Minnesota, have invented certain new and useful Improvements in Traction-Machines, of which the following is a specification.

The primary object of my invention is to provide a traction machine having a steering wheel to run in the furrow and equipped with means to prevent the edge of the wheel rim from digging into the wall of the furrow and climbing out of the furrow.

A further object is to provide improved means for raising and lowering the furrow wheel to compensate for the difference in length of the wheel that is running in the furrow and the one that is traveling on the land.

Other objects of the invention will appear from the following detailed description.

The invention consists generally in various constructions and combinations, all as hereinafter described and particularly pointed out in the claims.

In the accompanying drawings forming part of this specification,

Figure 1 is a side elevation of a traction machine embodying my invention,

Fig. 2 is a detail view, showing the raising and lowering device in section and also illustrating the means mounted in the wheel rim to bear on the wall of the furrow.

Figs. 3 and 4 are detail views of the raising and lowering mechanism,

Fig. 5 is a detail sectional view, showing the preferred manner of mounting the furrow wall plate in the wheel rim.

In the drawing, 2 represents a traction machine having a truss frame 3 at the forward end in which is mounted an upright sleeve 4 on a vertical pivot bolt 5. This sleeve is rocked back and forth in its bearing by means of the arm 6 that is connected with the steering post. Mounted on the sleeve 4 is an upright bracket 7 having guides 8 therein for a vertically movable slide 9 on the lower end of which a wheel spindle 10 is mounted. This slide has a longitudinal slot 11 therein to receive a bolt 12 which passes through said slot and into the bracket 7. Vertical movement of the sleeve is obtained by means of a threaded rod 13 having an end 14 to receive an

operating tool and engaging a threaded socket in the lug 15 on said slide, longitudinal movement of the screw being prevented by a collar 16. When this screw is revolved, the slide will be moved vertically in the bracket to raise or lower the wheel spindle. 17 is a wheel, mounted on the spindle 10 and having an annular rib 18 thereon to dig into the bottom of the furrow and prevent lateral slippage of the wheel, the vertical adjustment of this wheel and spindle compensating for the difference in level of this wheel and the one on the opposite side of the machine and adapting one wheel to run in the furrow and the other on the land while the machine frame is supported in a substantially level position.

A wheel of this kind, rocked back and forth to steer the machine and having the edge of the rim adjacent to the wall of the furrow, would frequently dig into the wall and climb out of the furrow, requiring constant attention on the part of the driver to accurately steer the machine.

To obviate this difficulty, I provide a disk 19 fitting within the wheel rim and having preferably an annular flange 20 for securing the disk to the rim and a rounded obtuse angle or bend 21 formed between the vertical portion of the disk and the flange 20. This rounded portion projects outwardly beyond the edge of the wheel rim and bears on the wall of the furrow, the angle of the bend being such that when the wheel is turned into the furrow wall the disk will slip thereon and keep the wheel in the bottom of the furrow, and even if the rounded portion of the disk should ride up a short distance on the furrow wall it soon will slip back and direct the wheel again to its normal running position in the bottom of the furrow. In this way the machine can be easily steered and the guiding wheel kept in the furrow without attention. The angle of the bend between the upright and flared portion of the disk may, of course, be modified to suit different conditions, but it is preferably of about the angular relation to the wheel and furrow wall as shown in the drawing.

In various ways the details of construction may be modified and still be within the scope of my invention.

I claim as my invention:

1. A traction machine having forward carrying and guiding wheels, one of them

- mounted to run in the furrow and a disk mounted in said furrow guiding wheel and having a rounded portion to fit into the angle formed by the bottom of the furrow 5 and the side wall and bear on the furrow wall to prevent the rim of the wheel from cutting into said wall.
2. A traction machine having forward carrying and guiding wheels, means for adjusting one of them to run in the furrow, 10 a disk mounted in the rim of said wheel and having a flange fitting within said rim, said disk projecting inwardly beyond the inner edge of the wheel rim in a plane at

right angles substantially to the tread of 15 said wheel and having a rounded face at its junction with said flange to ride on the wall of the furrow, for the purpose specified.

3. A traction machine having a forward guiding wheel mounted to run in the furrow, and means mounted on the wheel and encircled by the rim thereof and projecting outside said rim and having a rounded annular corner for bearing on the vertical 20 wall of the furrow, for the purpose specified. 25

In witness whereof I have hereunto set my hand this 23d day of April, 1915.

HARRY W. ADAMS.
